Patented Aug. 3, 1920.

UNITED STATES PATENT OFFICE.

ROBERT G. STEELE, OF KELSO, SASKATCHEWAN, CANADA.

ADJUSTABLE SCREEN FOR THRESHING-MACHINES.

1,348,668.

Specification of Letters Patent.

Patented Aug. 3, 1920.

Application filed January 20, 1919. Serial No. 272,168.

To all whom it may concern:

Be it known that I, ROBERT G. STEELE, a subject of the King of England, residing at Kelso, in the Province of Saskatchewan, 5 Dominion of Canada, have invented certain new and useful Improvements in Adjustable Screens for Threshing-Machines; and I do hereby declare the following to be a full, clear, and exact description of the 10 invention, such as will enable others skilled in the art to which it appertains to make and use the same.

The invention relates to a screen or sieve, and more particularly to the class of adjustable screens for use in threshing machines, grain separators or the like.

The primary object of the invention is, the provision of a screen of this character wherein, the chaff and straw will be separated from the grain by the current of air from the fan in the separator or threshing machine, and such chaff and straw will not bank or lay on the screen, nor will the grain be blown with the chaff or straw during the operation of cleaning the grain.

Another object of the invention is the provision of a screen of this character, wherein the construction thereof is novel in form so that the same can be readily adjusted to suit the use thereof when separating different kinds of grain such as wheat, oats, flax, rye, barley or any other grains or seeds and without the loss thereof, or the carrying thereof with the straw or chaff, during the separating process in the thresher or separator.

A further object of the invention is, the provision of an adjustable screen of this character which is simple in construction, 40 readily and easily adjusted, durable, strong and reliable in its purpose and inexpensive to manufacture.

With these and other objects in view, the invention consists in the features of construction, combination and arrangement of parts as will be hereinafter fully described, illustrated in the accompanying drawing and pointed out in the claims hereunto appended.

50 In the accompanying drawing:

Figure 1 is a fragmentary vertical sectional view through a thresher showing the screen constructed in accordance with the invention, therein.

55 Fig. 2 is a fragmentary top plan view of the screen.

Fig. 3 is a bottom plan view.

Fig. 4 is a vertical longitudinal sectional view.

Fig. 5 is a sectional view on the line 5—5 60 of Fig. 2.

Fig. 6 is a sectional view on the line 6—6 of Fig. 2.

Similar reference characters indicate corresponding parts throughout the several 65 views in the drawing:

Referring to the drawing in detail, A, designates generally the fan of a grain separator or thresher, and B, the sieve or screen through which the blast of air from the 70 fan is directed for the cleaning of the grain to separate the chaff and straw therefrom in the operation of the thresher or separator, the screen being of the adjustable type hereinafter fully described.

75 The screen or sieve B, comprises a supporting frame plate 10 which has fixed to its underside intermediate and outer longitudinal guide strips 11 and slidably fitted in the open center of the frame plate 10 is 80 the adjustable screen section, which includes a frame 12 supported upon the strips 11 and formed with spaced parallel transversely disposed perforated webs 13 constituting screening bars for the movable 85 frame 12, which is adjusted in a manner presently described.

Superimposed upon the supporting frame plate 10 is the stationary screening frame section 14 which is also formed with transversely disposed perforated webs 15, constituting stationary screening bars to cooperate with the webs or bars 13 of the movable screening frame.

These webs have one edge bent upwardly 95 to form grain retarding lips 16, which rise above the section 14, and constitute guards for the grain when subjected to the blast from the fan A, for the cleaning of the grain by separating the chaff therefrom, so 100 as to avoid the carrying of the grain with the traveling chaff with resulting loss of the grain. A lip or guard 16' is also bent obliquely up from the frame to prevent escape in the opposite direction.

105 The webs or perforated bars 13 and 15 in their spaced relation, form openings 17 therebetween and the webs 13 on adjustment of the frame 12 will register with the openings 17 between the webs 15 in the section 14, yet the perforations in the webs 13 and 15 will not close the screen to shut off the

blast from the fan A, and thus, the screen will be clean of chaff and straw when the said screen is adjusted for the cleaning of the different kinds of grain or seeds.

5 Secured on the stationary section 14, longitudinally thereof are intermediate and outer upstanding reinforcing ribs 18 which strengthen the screen and hold its lips rigid.

Fastened to the section 12 at its under side 10 and depending through the frame 10 are brackets 19 in which is mounted a connecting rod 20 for loosely connecting to said section, links 21, which are loosely connected to the cranks 22 of a rocking adjusting shaft 15 23, journaled in bearings 24 on the supporting frame plate 10 near one end thereof and at its under side. The shaft 23 is formed with an operating lever 25 with which is connected a fastening device 26 20 mounted in a segment 27 on and rising from the supporting frame plate 10, the fastener 26 being engaged for adjustment in a slot 28 in said segment 27 so that the lever 25 can be locked in its adjusted position. 25 On working the lever the slideable screen 12 can be adjusted relative to the stationary screen 14 for the use of the screen for the cleaning of grain according to the nature of that particular character of grain or 30 seeds, to be cleaned.

From the foregoing it is thought that the construction and manner of use of adjustable screen will be clearly understood and therefore a more extensive explanation has 35 been omitted.

What is claimed is:

1. The herein described screen comprising a supporting frame, a fixed screen sec-

tion including a frame rigidly carried by and above said supporting frame and having spaced transverse webs bent upward at one edge to form grain-retarding lips, one end bar of the frame of this section being also bent upward to form a lip, an adjustable screen section including a frame slidably mounted between said supporting and fixed frames and having transverse webs spaced to correspond with those in the fixed section, and means carried by the supporting frame for altering the position of said adjustable section to set its webs more or less across the spaces between the webs of the fixed section. 45

2. The herein described screen comprising a supporting frame, a fixed screen section including a frame rigidly carried by and above said supporting frame and having spaced transverse webs provided with perforations, an adjustable screen section including a frame slidably mounted between 50 said supporting and fixed frames and having transverse webs spaced to correspond with the spacing of those in the fixed frame and also provided with perforations, and means for adjusting the position of this section to set its webs across the spaces in the fixed section or underlying the webs thereof so that the perforations in the respective webs register, or at points between. 65

In testimony whereof I affix my signature 70 in the presence of two witnesses.

ROBERT G. STEELE.

Witnesses:

GLADYS DUNBAR,
C. N. SYME.
